UNITED STATES PATENT OFFICE.

PAUL H. BURDICK, OF GENEVA, ILLINOIS.

TYPEWRITING MACHINE.

Application filed September 3, 1920. Serial No. 407,928.

To all whom it may concern:

Be it known that I, PAUL H. BURDICK, a citizen of the United States of America, and a resident of Geneva, county of Kane, and 60 State of Illinois, have invented certain new and useful Improvements in Typewriting Machines, of which the following is a specification.

My invention relates in general to typewriting machines, and the object of the invention may be stated in broad terms to be the provision of a new and improved machine of this class, operating on new principles and including features tending to 10 greater speed in operation and less fatigue and strain on the part of the operator.

More specifically, I provide a typewriting machine having keys which are not individual to the several characters which are required to be written, but which on the contrary are considerably less in number than such characters, and correspond rather to the fingers of the operator in number and position; together with means, preferably electrical in character, whereby the operation of the keys singly or in combination will serve to separately control the type bars of the machine. Since the fingers of the operator do not change their position over the keys 20 and since no powerful striking movements are required to operate them, the process of writing with my improved machine is far less fatiguing than with the machines in common use. I provide, furthermore, a typewriting machine having duplicate sets of keys, one set for each hand of the operator, and each set capable of writing all the letters or characters in use. This makes it possible for the operator to always use her 25 two hands alternately while writing, thus greatly increasing the speed of operation.

The principles of the invention as explained above may be incorporated in an entirely new typewriting machine having the usual writing mechanism but omitting the standard keyboard, my improved keyboard being substituted therefor; or the new keyboard and associated mechanism may be constructed as a separate unit adapted to 30 function in connection with any standard make of typewriter. The latter form is the preferred one, and is the embodiment of the invention which will be described herein-after, reference being had to the accompanying drawings.

Referring to the drawings, Fig. 1 is a top

view of a standard typewriting machine mounted on the control unit, the view showing clearly the arrangement of the new keyboard.

Fig. 2 is a side view of the apparatus shown in Fig. 1, and shows the general shape and construction of the control unit. A portion of the side of the unit is cut away at the rear in order to show the arrangement 65 of the operating magnets.

Fig. 3 is a detailed drawing showing the preferred method of constructing the operating magnets, and the method of attaching the armatures to the type bars.

Fig. 4 is a detail drawing of one of the keys showing the method of mounting the contact springs controlled thereby.

Fig. 5 is a circuit diagram showing the manner in which the operating magnets are 75 controlled by the keys through the medium of relays.

Inasmuch as the typewriting machine itself is old and well known, no detailed explanation of the operation thereof will be 80 given and no attempt has been made to show all the mechanical details in the drawings. The line spacer, marginal stops, and all the other usual attachments except the word space bar and the shift are manually 85 operated in the usual manner. The explanation will, therefore, be confined to the control unit and its operation in actuating the type bar magnets, whereby the typewriting machine is operated. Referring first to 90

Figs. 1 and 2, all the apparatus with the exception of the operating magnet armatures is mounted in a single unitary structure which comprises a box or casing 10, made of wood or other suitable material and adapted 95 to form a base for the typewriting machine with which the apparatus is to be used. At the rear and underneath the typewriter the hollow base or casing contains the operating magnets and the controlling relays, while the forward portion forms a key shelf upon which the keys are mounted. The keys are twelve in number. Keys 1 to 6 are operated by the right hand of the operator, keys 3 to 6 being finger keys, while keys 1 and 2 are 100 actuated by the thumb. The corresponding keys for the left hand are indicated by reference numerals 1' to 6' inclusive. As shown in the drawing the keys resemble piano keys and are of about the same size. Each key 105 controls a set of contact springs by which the necessary electrical connections are made.

The arrangement of these springs and the construction of one of the keys may be best explained by referring to Fig. 4, which is a section through the key shelf 5 between keys 4 and 5. The key 4 may be constructed of wood and is supported on the pivot 13. The upper surface is formed of an ivory or celluloid plate 12. The spring 14 serves to restore the key after 10 being depressed, and the upward movement is limited by the felt strip 16. A similar strip of felt 15 limits the downward movement. The spring combination comprises the stationary springs 20 and 21 and the 15 movable springs 22, 23, and 24. The former springs are attached by means of a machine screw and insulating washers to the flat steel strip 25 which extends the entire width of the base and has both ends bent down 20 to form legs which are suitably attached to the base. This strip supports all the stationary springs which are associated with the finger keys. A similar strip (not shown) is properly positioned beneath the 25 thumb keys and supports the stationary springs which are therewith associated. The movable springs 22, 23, and 24 are secured to the under surface of the key 4 by means of another machine screw and are 30 also properly spaced and insulated from each other by washers or fibre insulators. The springs are adjusted so that springs 21 and 24 are normally in engagement as shown. When the key is depressed at the 35 first downward movement these two springs separate, and just before the downward movement is completed springs 22 and 23 simultaneously engage springs 20 and 21, respectively.

40 The operating magnets are, of course, equal in number to the number of type bars, with extra magnets for operating the word space bar, the shift, and the shift release. The location and arrangement of these magnets is shown clearly in Figs. 1 and 2. The 45 magnets are arranged in three rows, the rear most row being located about two and one half inches forward of the point at which the type bars are pivoted. By arranging the magnets in three rows, fairly large and 50 powerful magnets may be used, notwithstanding the close spacing of the type bars, and a quick and positive operation is insured. Each row of magnets is mounted 55 on a flat strip of brass, one of these strips being indicated by the reference character 30. Each brass strip extends the entire width of the base and the ends are bent down to form legs by means of which the 60 strip is supported.

The construction of the magnets and armatures can best be explained with reference to Fig. 3. The magnet there shown comprises a soft iron core 35 provided at 65 opposite ends with fibre discs 36 which en-

close the winding space. In order to provide a return path for the magnetic flux, the entire magnet is enclosed in a soft iron shell 34. The top of the shell is cut away at the sides for a short distance as shown, 70 leaving two projecting members 37 and 38, whose extremities are even with the top of the magnet core. The armature 33 is of about the same width as the diameter of the core and is attached to the type bar by 75 means of a metal strip 32. The armature is cut out or recessed on the under side and the strip 32 passes entirely around it, the two sides of the bracket thus formed being clamped together by means of rivet 39. The 80 two halves of the bracket pass on opposite sides of the type bar and are pivotally attached there to by means of machine screw 40.

Having described the mechanical construction of my improved typewriter, or typewriter control mechanism, as it is perhaps more properly called, I will now describe the means by which the operation of the keys, singly and in combination, effects the separate actuation of the operating magnets. This means, as is understood, is preferably electrical in character and consists of relays together with suitable circuits for accomplishing the desired object. 95

Referring to Fig. 5, at the upper right hand corner of the sheet, the six keys for the right hand of the operator are indicated by reference characters 1 to 6, inclusive. The keys for the left hand, indicated by reference characters 1' to 6', inclusive, are shown at the left. At the lower left hand portion of the sheet are shown the operating magnets. These magnets are forty-five in number, providing for as many separate characters as are used on standard typewriting machines, and are arranged in three groups. Relays 50 to 57, inclusive, are operated by the finger keys and control the selection within groups, while relays 60 and 61 are 100 operated by the thumb keys and control the group selection. Relays 58 and 59 are common to the keys of the left and right hands, respectively, and their function is to prevent interference between the two sets of keys. 110 Relay 62 is a double wound relay which is inserted in the main battery supply lead extending to the operating magnets for the purpose of limiting the operating time of the magnets. 115

As stated hereinbefore, all of the forty-five operating magnets may be separately controlled by the six keys of either hand used separately and in combination. Various schemes may be employed to accomplish 120 this, but the plan adopted is to use the four finger keys to simultaneously select operating magnets in three different groups, while the thumb keys are used to control the selection of groups. By using four keys singly 125

130

and in combination, fifteen different combinations are possible. Thus each group contains fifteen operating magnets. All the magnets of the first group are normally connected to the battery and thus are operable by means of the finger keys alone. Each thumb key is adapted by means of a relay to transfer the battery connections to a different group of magnets, which provides for 10 three groups of magnets or forty-five in all.

In assigning the different key combinations to the different letters and characters which have to be written, regard has been had to the relative frequency of the different 15 letters and characters as they occur in ordinary English printed matter, with a view to associating the most simple combinations with the letters and characters of the greatest frequency.

20 The following table shows the arrangement that has been adopted:

Letter or character.	Key combination.
To write E e.....	depress key 3
To write T t.....	depress key 4
To write O o.....	depress key 5
25 To write A a.....	depress key 6
To write N n.....	depress keys 3 and 4
To write I i.....	depress keys 4 and 5
To write R r.....	depress keys 5 and 6
To write S s.....	depress keys 3 and 5
To write H h.....	depress keys 4 and 6
To write D d.....	depress keys 3 and 6
To write L l.....	depress keys 3, 4, and 5
30 To write U u.....	depress keys 4, 5, and 6
To write C c.....	depress keys 3, 4, and 6
To write M m.....	depress keys 3, 5, and 6
To write P p.....	depress keys 3, 4, and 6
To write F f.....	depress keys 2 and 3
To write Y y.....	depress keys 2 and 4
To write W w.....	depress keys 2 and 5
To write G g.....	depress keys 2 and 6
35 To write B b.....	depress keys 2, 3, and 4
To write V v.....	depress keys 2, 4, and 5
To write K k.....	depress keys 2, 5, and 6
To write X x.....	depress keys 2, 4, and 6
To write Z z.....	depress keys 2, 3, and 6
To write Q q.....	depress keys 2, 3, 5, and 6
To write ,.....	depress keys 2, 3, 4, and 5
To write . /.....	depress keys 2, 4, 5, and 6
40 To write : /.....	depress keys 2, 3, 4, and 6
To write 3 #.....	depress keys 1 and 3
To write 4 \$.....	depress keys 2 and 5
To write 5 %.....	depress keys 1 and 6
To write 6	depress keys 1, 3, and 4
To write 7 &.....	depress keys 1, 4, and 5
To write 8	depress keys 1, 5, and 6
To write 9 (.....	depress keys 1, 3, and 5
45 To write -	depress keys 1, 4, and 6
To operate word space bar	depress keys 2, 3, 4, 5, and 6
To operate shift	depress keys 1, 3, and 6
To operate shift release	depress keys 1, 4, 5, and 6

The above table includes all the letters and characters that are commonly used and 50 requires only forty combinations, which leaves five combinations for any special characters that may be desired. Or these remaining combinations may be used to operate some of the mechanical devices that 55 are ordinarily operated manually, such as the tabulator, and the line spacer, for example.

The operation of writing certain characters will now be described with a view to 60 explaining the circuits more in detail. Consider first the letter E. According to the table this letter is written by depressing key 3. When this key is actuated a circuit is completed which extends as follows: 65 Ground at G², armature 80 and its resting

contact, winding of common relay 59, conductor 81, contact spring 74 and its resting contact, contact spring 75 and its resting contact, contact spring 76 and its working contact, contact spring 21 and its resting 70 contact, contact spring 78 and its resting contact, contact spring 79 and its resting contact, conductor 83, lower make contact of key 3, conductor 84, and the winding of relay 50 to battery. Upon the closure of 75 the above circuit relays 59 and 50 are energized in series and the former relay disconnects ground G² from relay 58 in order to prevent interference in case one or more keys should be accidentally depressed with 80 the left hand before key 3 is released. When relay 50 energizes and attracts its armature 85 a circuit is completed as follows: Ground at G⁴, armature 85 and its working contact, armature 89 and its resting contact, armature 90 and its resting contact, armature 91 and its resting contact, conductor 101, winding of magnet 65, resting contact of armature 66 and the said armature, resting contact of armature 67 and the said armature, conductor 68, left hand winding of relay 62, and resting contact of armature 105 and the said armature to battery. The left hand winding of relay 62 is of low resistance 85 and the said relay and magnet 65 are energized in series. Magnet 65 is located beneath the particular type bar which is associated with the letter E and as a result of its energization the type bar is actuated to write such letter, the same as if the proper 90 key were struck manually by the operator.

Relay 62, as before stated, is provided to limit the operating time of the magnets and its functions as follows: Assuming that a 24 volt operating battery is used, the resistance 105 of the operating magnets such as magnet 65 may be about 30 ohms. The resistance of the left hand winding of relay 62 is about 1 ohm and its right hand winding has a resistance of about 500 ohms. The relay is 110 provided with a slug of copper on one end of the core to render it somewhat slow to pull up its armature. Now when the circuit of magnet 65 is closed as just described, the magnet is instantly energized in series 115 with the one ohm winding of relay 62. An instant later, and just as the magnet has completely attracted its armature, relay 62 operates its armature 105, thereby removing the short circuit from its 500 ohm winding 120 and connecting this winding in the circuit also. This has practically the same effect on magnet 65 as the complete opening of the circuit would have, as the current flow is reduced to a small fraction of its initial 125 value, and the magnet accordingly retracts its armature. Relay 62 remains energized, however, and retains its high resistance winding in the circuit until the key is released and the circuit is broken at the re- 130

lay 50. By properly adjusting relay 62, short powerful current impulses may be given the magnets of just the right length to give the effect of striking the keys by a 5 rapid and experienced typist.

The letter E is written without using either of the thumb keys, and the writing of several other letters will now be explained in order to show the function of 10 these keys clearly. Suppose the letter Z is to be written. According to the table the combination for this letter requires keys 2, 3, and 6 to be depressed. Key 2 is the second thumb key for the right hand, while 15 keys 3 and 6 are the first and fourth finger keys. The keys are all depressed simultaneously, and with all the keys in their depressed position a circuit is closed for relay 61 as follows: Ground at G^2 , armature 80 20 and its resting contact, winding of relay 59, conductor 81, contact spring 74 and its resting contact, contact spring 75 and its working contact, contact spring 76 and its working contact, contact spring 21 and its resting contact, contact spring 78 and its resting contact, contact spring 79 and its working contact, conductor 83, lower make contact of 25 key 2, conductor 69, and the winding of relay 61 to battery. Relay 61 is energized 30 and by attracting its several armatures disconnects the operating battery from all the magnets of the first group and connects said battery to all the magnets of the second group. At the same time that the above circuit 35 is completed for relay 61, circuits are completed for relays 50, 54, 55, 56, and 57 by the keys 3 and 6. The circuit of relay 50 has already been traced and the circuit of the other four relays, which are all energized 40 in parallel, is of a similar character. The five last mentioned relays being in operated position, a circuit is completed for magnet 64 as follows: Ground at G^4 , armature 85 and its working contact, armature 45 89 and its resting contact, armature 90 and its resting contact, armature 91 and its working contact, conductor 102, winding of magnet 64, working contact of armature 70 and the said armature, resting contact of 50 armature 71 and the said armature, conductor 68, left hand winding of relay 62, and the resting contact of armature 105 and the said armature to battery. The above circuit 55 is closed by relays 50, 54, and 61, operating simultaneously, and as a result magnet 64, which is positioned beneath the type bar corresponding to the letter Z, is operated momentarily to strike the required letter.

The process of writing the figure 5 will 60 now be described briefly in order to explain the function of the first thumb key. Consulting the table, it will be found that the proper combination for this character is keys 1 and 6. These two keys are depressed 65 simultaneously and key 1 closes a circuit

for relay 60, while key 6 closes a circuit for relays 54 to 57, inclusive. In view of the detailed circuit descriptions already given, these circuits may be traced without difficulty. Relays 54 and 60 being now in 70 operated position, the following circuit is completed for magnet 63: Ground at G^4 armature 85 and its resting contact, armature 86 and its resting contact, armature 87 and its resting contact, armature 88 and 75 its working contact, conductor 103, winding of magnet 63, resting contact of armature 72 and the said armature, working contact of armature 73 and the said armature, conductor 68, left hand winding of relay 62, 80 and the resting contact of armature 105 and the said armature to battery. By the closure of the above circuit magnet 63 is operated momentarily to strike the figure 5.

In view of the foregoing it is thought 85 that the manner of operating the remaining magnets to write the other letters and characters will be understood readily without further explanations. It is understood, of course, that the battery connections of all 90 magnets are controlled by relays 60 and 61 in the same manner that the connections of the first nine magnets at the left are controlled. That is, these two relays are in practice provided with sufficient contact 95 springs to control the battery connections of all the magnets. Since the connections are all the same, however, it is considered unnecessary to show the complete wiring of more than nine, as this number is sufficient to illustrate the selective principle employed. If desired, and this is perhaps the preferable procedure, the contact springs associated with each group of magnets may be divided among several relays and the 100 relays of each group can be connected in series or in parallel. This is the plan that has been followed with the contact springs controlled by keys 5 and 6 through the medium of relays 52 to 57, inclusive.

As stated hereinbefore, all the letters and characters can be made with either hand. Keys 1' to 6', inclusive, are connected in multiple with keys 1 to 6, inclusive, and operate the same relays; it is therefore immaterial whether the right or left hand be used in striking any particular letter. This arrangement is of great utility as it permits the operator to always use her two hands alternately. The first letter in a 115 word may be written with the right hand, the next letter with the left, the next with the right, and so on. Writing thus becomes automatic and maximum speed is attained. Interference between the right and left hands is prevented by the series relays 58 and 59, each of which interrupts the ground connection to the keys associated with the other. If a right hand key is depressed 120 relay 59 is energized and disconnects ground 125 130

from the left hand keys, while the depression of any left hand key will energize relay 58 to disconnect ground from all the right hand keys. Due to this provision if the operator while writing rapidly should accidentally depress a key with one hand before the key depressed with the other hand is released, no harm will be done.

One other circuit device remains to be explained. It will be noticed that the conductor 81, which supplies ground to all the right hand keys, is looped through contact springs on all the keys before connecting with conductor 83. This circuit arrangement is provided to guard against slight inaccuracies in depressing keys simultaneously. To explain this, suppose that direct ground is supplied to all the keys and that the letter N is to be written, requiring keys 3 and 4 to be depressed simultaneously. Now if key 3 is depressed slightly before key 4, as soon as the former key closes its make contact, relay 50 will be energized and the machine will start to write the letter E, which will be changed to the letter N as soon as key 4 closes its make contact and energizes relay 51. It will be readily seen that confusion would often result with such a circuit arrangement unless the operator were extremely careful to depress the keys exactly together. By the provision of the loop circuit such extreme accuracy is not required. It is only necessary that the operator shall start all keys which are to be depressed before any one of them is entirely operated. When the key which is started first leaves its normal position it breaks the loop circuit and this circuit is held open by one key or the other until the last key is entirely depressed and all make contacts are closed. Since the keys have a relatively long stroke, the operating requirements pointed out above are easily met with a little practice and accurate writing is insured.

Having described my invention, what I consider to be new and desire to have protected by Letters Patent will be pointed out in the appended claims.

What I claim is:

1. In a typewriting machine, a plurality of writing devices, magnets for operating said devices, keys for controlling the circuits of said magnets, and a common conductor included in all of said circuits, an automatic device connected in series with said conductor and effective to limit the time during which any magnet can remain operated.

2. In a typewriting machine, a plurality of writing devices, magnets for operating said devices, keys and associated means for closing the circuits of said magnets to operatively energize the same, and an automatic device comprising a relay which is energized in series with any energized magnet to de-

energize such magnet after a definite time interval.

3. In a typewriting machine, a plurality of writing devices, a set of keys, means for operating said devices separately by depressing different combinations of keys, and means active whenever a plurality of keys constituting a combination are simultaneously in motion for preventing faulty operation due to failure of such keys to reach their final depressed positions simultaneously.

4. In a typewriting machine, a plurality of separate writing devices, magnets for operating said devices, relays for controlling the circuits of said magnets, keys operable in different combinations to energize said relays, a conductor common to all the relay circuits and extending through all said keys in series, and contact springs controlling the series connections and so adjusted that the said conductor is open only while any key is passing from normal to fully operated position.

5. In a typewriting machine, a plurality of separate writing devices, magnets for operating said devices, relays for controlling the circuits of said magnets, keys operable in different combinations to energize said relays, a conductor common to all the relay circuits and extending through all said keys in series, a pair of contact springs at each key included in said conductor when said keys are normal, and an additional contact spring at each key for closing said conductor when the keys are depressed.

6. In a typewriting machine including writing devices, magnets for operating said devices, right and left hand key sets for controlling the circuits of said magnets, a common conductor for connecting the operating battery with all the keys of the right hand key set, a similar conductor associated with the left hand key set, means responsive to current flow in the said first conductor for opening the said second conductor, and means responsive to current flow in the said second conductor for opening the said first conductor.

7. In a typewriting machine, a plurality of separate writing devices, individual magnets for operating said devices, right and left hand key sets for controlling the circuits of said magnets, both sets being normally operative, a common conductor which is included in the circuit of any magnet actuated through the medium of the right hand key set, a similar conductor associated with the left hand key set, a relay connected in series with said first conductor for opening the said second conductor, and a second relay connected in series with said second conductor for opening the said first conductor.

8. In a typewriting machine, a plurality of separate writing devices, individual mag-

nets for operating said devices, right and left hand key sets for controlling the circuits of said magnets, both sets being normally operative, a relay for opening all of the circuits controlled by the left hand key set, means for energizing said relay when any key in the right hand key set is depressed, a second relay for opening all of the circuits controlled by the right hand key set, and means for energizing said second relay when any key in the left hand key set is depressed.

9. In a typewriting machine, a plurality of separate writing devices, individual operating magnets for said devices, said magnets being divided into groups, thumb keys and finger keys, relays controlled by the thumb keys for selecting desired groups of said magnets, and relays controlled by the said finger keys for selecting individual magnets in selected groups.

10. In a typewriting machine, a set of finger keys, a plurality of writing devices, individual magnets for operating said devices, relays operated in permutations by means of said keys for separately energizing said magnets, a second plurality of writing devices and individual operating magnets therefor, a thumb key, and a relay controlled by said thumb key for shifting the control of said permutational relays from the magnets associated with the said first plurality of writing devices to the magnets associated with the said second plurality of writing devices.

11. In a typewriting machine, a set of finger keys, a plurality of writing devices, individual magnets for operating said devices, relays operated in permutations by means of said keys for separately energizing said magnets, two additional pluralities of writing devices and associated operating magnets, two thumb keys, and two relays controlled by said thumb keys, respectively, for shifting the control of said permutational relays from the magnets associated with said first plurality of writing devices to the magnets associated with either of said additional pluralities of writing devices.

50 12. In a typewriting machine, a set of finger keys, separate writing devices corresponding to each key and additional writing devices equal in number to the total number of possible combinations of said keys, all of said writing devices constituting a set which is normally under the control of said keys, another set of writing devices equal in number to the said first set, and a thumb key operable to shift the control of said finger keys from the writing devices of the first set to the writing devices of the second set.

65 13. In a typewriting machine, a set of finger keys, separate writing devices corresponding to each key and additional writing devices equal in number to the total

number of possible combinations of said keys, all of said writing devices constituting a set which is normally under the control of said keys, a plurality of other sets of writing devices similar to said first set, and a plurality of thumb keys each adapted to shift the control of said finger keys from the writing devices of said first set to the writing devices of one of said other sets.

14. In a typewriting machine, a plurality of separate writing devices, individual operating magnets for said devices, said magnets being divided into groups, group selecting relays, there being a relay for each group except one, permutational relays for selecting individual magnets in selected groups, keys for energizing the said group selecting relays, and additional keys operated singly and in combination for energizing said permutational relays.

15. In a typewriting machine, a plurality of separate writing devices, individual operating magnets for said devices, said magnets being divided into two main groups, each main group being divided into two sub-groups, and each sub-group being divided into two sub-sub-groups, relay mechanism controlled by a key for selecting a main group, additional relay mechanism controlled by another key for selecting a sub-group in the selected main group, and still other relay mechanism controlled by another key for selecting a sub-sub-group in the selected sub-group.

16. In a typewriting machine, a plurality of separate writing devices, individual operating magnets for said devices, a conductor for supplying current, a series of groups of relay contacts whereby said conductor is divided and subdivided into a plurality of branches, the number of branches being doubled at each group of contacts, and individual connections from the branches emanating from the last group of relay contacts to the said operating magnets.

110 17. In a permutational relay selecting device for controlling the operating magnets of a typewriter, a series of relay mechanisms each comprising one or more relays, a single armature controlled by the first of said relay mechanisms having resting and alternate contacts, similar armatures on the other mechanisms, the number of armatures on any mechanism being double the number on the preceding mechanism, connections from the resting and alternate armature contacts at each mechanism except the last to the armatures of the next mechanism, and connections from the resting and alternate armature contacts of the last mechanism to the typewriter operating magnets.

18. The combination, with a typewriting machine having type bars and a key set comprising manually operable keys individual to said bars and permanently at-

tached thereto mechanically, of an auxiliary mechanism for operating said typewriting machine, said auxiliary mechanism comprising a set of keys less in number than said type bars, means for suitably supporting said last set of keys adjacent the said manually operable key set, whereby keys in either set may be depressed at the option of the operator, and means for separately operating said type bars by depressing keys of the auxiliary set singly and in combination.

19. The combination, with a typewriting machine comprising type bars and a plurality of manually operable actuating keys, there being one such key individual to each bar, of an auxiliary mechanism for operating said typewriting machine at the option of the operator, said mechanism comprising a container serving as a base for the said typewriting machine, auxiliary keys in the forward end of said container positioned in front of said manually operable keys, magnets in the rear of said container for operating said type bars, and circuit arrangements whereby said magnets may be separately energized by depressing said auxiliary keys singly and in combination.

20. The combination, with a typewriting

machine comprising type bars and a plurality of manually operable actuating keys, there being one such key individual to each bar, of an auxiliary mechanism for operating said typewriting machine at the option of the operator, said mechanism comprising a base for supporting said typewriting machine, a forwardly extending key shelf containing right and left hand auxiliary key sets, and individual operating magnets for said typebars separately controllable from either of said auxiliary key sets.

21. The combination, with a typewriting machine having a bank of manually operable keys, there being an individual key for each letter, and each key being supported on a pivoted bar, of an auxiliary device comprising a set of magnets having armatures connected to said bars, a second set of keys less in number than said first set, and means intervening between the said second set of keys and the said magnets whereby the latter may be operated separately by depressing the keys of said second set singly and in combination.

Signed at Geneva, county of Kane, and State of Illinois, this 31st day of August, 1920.

PAUL H. BURDICK.
